UNITED STATES PATENT OFFICE.

HARRY J. KEELEY, OF LOS ANGELES, CALIFORNIA, ASSIGNOR TO NON-ELECTRIC FAN CO., A CORPORATION OF ARIZONA.

SPRING-MOTOR.

1,258,687.

Specification of Letters Patent. Patented Mar. 12, 1918.

Application filed January 12, 1917. Serial No. 141,934.

To all whom it may concern:

Be it known that I, HARRY J. KEELEY, a citizen of the United States of America, and a resident of Los Angeles, county of Los Angeles, and State of California, have invented certain new and useful Improvements in Spring-Motors, of which the following is a specification.

This invention relates to spring motors suitable for driving fans, phonographs, etc. The device is shown in the drawings as applied to a fan.

The main objects of the invention are to provide a silent, simple and highly efficient spring motor; to provide an improved arrangement of multiple balanced driving springs; to provide an improved arrangement of speed increasing gears for driving by spring motors; to provide an improved ratchet mechanism for the winding crank of the motor; to provide improved means for transmitting motion to a fan having an axis at right angles to the driving spindle; and to provide improved means for governing the speed of the fan.

An illustrative embodiment of this invention is shown in the accompanying drawings, in which:

Figure 1 is a vertical sectional view of a motor constructed according to this invention.

Fig. 2 is a horizontal sectional view taken on the line A—A of Fig. 1, and shows the arrangement of gearing.

Fig. 3 is a detail of the winding crank and shaft.

The design of spring motor shown in the drawings is intended to provide means suitable for driving fans for use in hospitals, where a silent mechanism is desirable, and also to provide spring driving means for fans for use in such localities where electric power is not available. It is desirable to have such motors operate for at least an hour or two upon a single winding of the springs, but yet to have the mechanism sufficiently light to make the device easily portable. It is therefore essential that the mechanical efficiency of the motor be comparatively high, involving small friction losses in the gears and driving mechanism thereof.

A circular bed plate 1 supports the motor and is provided with bosses 2, 3, 4 and 5 in which are journaled spindles for supporting the gears by means of which movement is transmitted from the springs to the driven fan. The plate 1 has a depression 6 at the location of said gears, as indicated by the dotted line 7 in Fig. 2, in order that the gears may run in oil contained in said depression. A plurality of feet or supporting pads 8 are secured to the under side of plate 1. A journal member 9 is secured to plate 1 at the location of bosses 10 thereof by means of screws 11.

Rotatably mounted within the journal member 9 and bearing against a bushing 12 thereof is a sleeve 13. This sleeve carries at its upper end a bevel gear 14 which may be secured to the sleeve by a key 15, as shown in Fig. 1, between the collars 16 and 17. Meshing with the gear 14 is a pinion 18 fast on a crank shaft 19 to which is secured the winding crank 20. The crank shaft 19 is journaled in a boss 21 formed in the casing member 22. The member 22 is spaced from the member 1 by an annular part 23 of the casing. Bolts 24 serve to retain the casing members 1, 22 and 23 in the proper fixed relation.

The driving springs 25 and 26 are coiled around the sleeve 13 and have their inner ends respectively secured to opposite sides of said sleeves, as indicated at 27 and 28. The outer ends of the springs are wrapped around posts 29 and 30, respectively located at opposite sides of, and securing in proper fixed relation, the circular or disk-shaped plates 31, 32 and 33 journaled on the sleeve 13. The plate 33 carries fast by means of the screws 34, an internal gear ring 35. The internal gear meshes with a pinion 36 which is fast to a gear 37 and journaled on spindle 38 extending upwardly from boss 2.

A gear 37 meshes with a pinion 39 fast to a gear 40 and journaled on spindle 41 extending upwardly from boss 3. Gear 40 meshes with a pinion 42 fast to a gear 43 and journaled on spindle 44 extending upwardly from boss 4. Gear 43 meshes with a pinion 45 secured to the upright spindle 46 which is journaled in boss 5 and in the

web portion 47 of the casing member 22. The fan 48 is fast on shaft 49 which is rotatably and slidably mounted in bushings 50 and a bearing member 51 integral with member 22 of the casing. The spindle 46 is connected to shaft 49 by a flexible shaft or coiled spring 52. This coiled spring serves the double function of transmitting motion to the fan at right angles to the 10 driving spindle 46 and to govern or limit the speed of the fan. During rotation of the fan, a certain predetermined wind pressure on the outer sides of the blades serves to slide the fan and its shaft 49 inwardly 15 in the bushings 50 and thereby cause the curve of the flexible member 52 to become more acute. By this means member 52 is more or less compressed and its resistance to turning is increased which results in limiting the speed of fan 48.

Rotation of the fan may be completely arrested by set screw 53 which is threaded in boss 51 and may engage the spindle 49. The inner end 54 of set screw 53 is slightly 25 enlarged after the screw has been tapped into the boss to prevent removal and loss thereof.

A guard 55 surrounds fan 48. This guard is supported on boss 51 by dowel pins 56 seated in recesses in the boss and secured to a transverse member 57 of the guard. The circular portion 58 of the guard is preferably stretched over the head of a screw 59 extending outwardly from casing member 35 22. The screw therefore serves to maintain the guard rigidly in the desired position. To remove the same it is only necessary to snap the circular portion 58 off of screw 59 and lift the guard and thereby unseat it 40 from the boss 51. The upper open portion of casing member 22 is preferably closed by a semicircular cap 60.

Backward rotation of the winding crank shaft 19 is prevented by a roller ratchet arrangement shown in Fig. 3. The spindle 19 is provided with recesses 61 of the shape shown and in which rest rollers 62. These rollers drop into said recess in the winding direction of rotation of shaft 19 while 50 wedging themselves between the inclined portion 63 of the recess and the inner surface of boss 21 when the shaft attempts to rotate backwardly under the action of springs 25 and 26. This roller clutch arrangement provides a very efficient and 55 silent ratchet.

In the operation of the device, the springs 25 and 26 are tensioned by rotating crank 20, thus through the pinion 18 and gear 14 60 rotating the sleeve 13 to which the inner ends of springs 25 and 26 are secured. When the crank is released, backward rotation of shaft 19 is prevented by the rollers 62 wedging between the shaft and the boss

within which it is journaled. Springs 25 65 and 26 are therefore wound together and likewise uncoiled together, rotating the disks 31, 32, and 33 as a unit and thereby rotating the internal gear 35 which is secured to the disk 33. Internal gear 35, through the train 70 of pinions and gears between it and the spindle 46, serves to rotate the latter spindle at a very considerable increase of speed over the rotation of internal gear 35. The fan is thus driven by its connection to spindle 75 46 through the flexible shaft 52 and is maintained at some predetermined maximum speed through the governing action of flexible shaft 52 which forms a more or less acute curve according to the wind pressure developed by the fan on the outer sides of the 80 blades.

By the above described arrangement of springs 25 and 26 in a pair, each operate together, but are respectively secured to opposite points on the stationary and driven members, and comparatively powerful action is effected without vibration, since the springs balance each other. Also in the arrangement of gearing wherein the motion is 90 transmitted from an internal gear inwardly to a central spindle the gearing may be compactly arranged in a comparatively small 95 space and still effect a considerable increase in speed. The flexible shaft 52 serves to eliminate the usual bevel gears employed for transmitting motion to shafts arranged at right angles, and also acts as a highly efficient governor, making unnecessary any separate means for governing the speed of the 100 fan.

Although but one specific embodiment of this invention has been herein shown and described, it will be understood that numerous details of the construction shown may be altered or omitted without departing 105 from the spirit of this invention as defined by the following claims.

I claim:

1. A device of the class described, comprising a motor, a shaft driven thereby, a second shaft at an angle to the first-named shaft, a fan secured to said second shaft, a flexible shaft connecting said two first mentioned shafts, and a bearing for said second shaft arranged to permit lengthwise movement of said shaft in the bearings according to the thrust developed by the rotation of the fan.

2. A device of the class described, comprising a motor, a shaft driven thereby, a fan carried by said shaft, bearings for said shaft permitting lengthwise movement of the shaft according to the thrust developed by the rotation of the fan, and means controlled by the lengthwise movement of said shaft governing the speed of said shaft.

3. In a spring motor, a driving spring and

means for winding the same, a shaft arranged to be driven by said spring, a second shaft having a fan arranged at right angles to said first mentioned shaft and connected therewith by a flexible shaft, bearings for said second shaft arranged therewith to permit said shaft to slide lengthwise in said bearings and thereby alter the arc of said

flexible shaft for the purpose of regulating the speed of said second shaft. 10

Signed at Los Angeles this 28 day of Feby. 1916.
